STEEPING PRESS

Leo Kohorn, Lima, Peru, assignor to Oscar Kohorn & Co., Ltd., New York, N. Y., a corporation of New York

Application August 27, 1947, Serial No. 770,941

3 Claims. (Cl. 100—50)

1

The present invention relates to an improved steeping press, and it relates more particularly to an improved steeping press of the automatic discharge type.

In the manufacture of rayon by the viscose process, one of the steps comprises converting cellulose into alkali cellulose. This is generally accomplished by steeping sheets of purified pulp into a caustic soda solution for a period of about an hour. During this period, the sheets of pulp swell and absorb a considerable amount of the caustic solution. Before the alkali cellulose may be shredded and xanthated, it is necessary to extract most of the solution absorbed by the pulp.

The equipment commonly employed in alkalizing cellulose sheets is known as a steeping press, and consists of a long horizontal vat of rectangular cross-section and having an open top. A plurality of parallel metal plates are positioned in and are slideable along the length of the vat, and support between them the sheets of pulp to be alkalized. Also positioned in the vat is a ram which is employed for expressing the excess alkali solution from the sheets of alkali cellulose, and may be operated by a screw device, hydraulic cylinder or any other suitable mechanism. In operation, the ram is brought to its retracted position, and sheets of cellulose are placed between the successively adjacent plates. The caustic soda solution is flowed into the vat to completely immerse the sheets of pulp for the desired period. The solution is then drained from the vat, and the ram actuated to express the excess solution to bring the sheets of alkali cellulose to the desired press ratio, that is, the ratio of the alkali cellulose and absorbed caustic to the dry cellulose content. Thereafter, the ram is retracted, the alkali cellulose sheets manually removed and transported to the following operation.

The manual removal of the sheets of alkali cellulose is highly undesirable for many reasons. The operation consumes considerable time and is hazardous to the operator. There have been many proposals to effect the mechanical discharge of the sheets of alkali cellulose from the steeping press, but these all possess numerous drawbacks.

It is, therefore, an object of the present invention to provide an improved steeping press.

Another object of the present invention is to provide a steeping press having an improved sheet discharge mechanism.

Still another object of the present invention is to provide a steeping press having an improved

2

sheet discharge mechanism characterized by rugged construction and positive operation.

The above and further objects of the present invention will become apparent from a reading of the following description, together with the accompanying drawing, wherein Figure 1 is an elevational view of a hydraulic-type steeping press with parts of the tracks 20 broken away, embodying the present invention; Fig. 2 is a detail sectional fragmentary view, taken along line 2—2 of Fig. 1, the fragment omitted being of substantially similar and symmetrical construction to that illustrated; and Fig. 3 is a detail fragmentary plan view, taken from line 3—3 of Fig. 2; Fig. 4 is a sectional view taken along line 4—4 of Fig. 2; and Fig. 5 is a fragmentary isometric view showing the cam and follower construction.

The present invention contemplates an open top vat, provided with a ram movable along the length of the vat, and having a vertically slideable gate at the end opposite the ram end. Within the vat are a first pair of guide rails or tracks, one of which is indicated by numeral 22a positioned along the side walls of the vat, and which slideably support sheet-partitioning plates. Slideably positioned outside the vat and arranged in alignment with the first pair of tracks, are a second pair of tracks, one of which is disclosed by the numeral 20. While the drawings illustrate only one each of the tracks 20 and 22a, it is believed clear that these tracks are duplicated within the vat 10 and outside the vat to form pairs of tracks. A mechanism is provided which also associates the gate and the second pair of tracks, that upon the raising of the gate, the second pair of tracks is urged into registry with the first pair of tracks. Another mechanism, also actuated by the sliding gate, urges locking pins 40 into complementary bores formed in the second pair of tracks, to lock them in registry with the first pair of tracks. The latter mechanism is provided with heavy weights, which by way of a series of levers positively retracts the locking pins 40 from the tracks upon the lowering of the gate.

Reference is now made to the drawings, wherein 10 designates a long tank or vat of rectangular cross-section reinforced by tension rods 46a and having a completely open top, through which may be inserted sheets of pulp. A ram 11a of substantially the same transverse cross section as the interior of the vat 10, is slideably positioned within the vat 10, and is supported at an end of a plunger 11, projecting through the end wall of the vat 10, by way of a fluid-tight fitting. The

plunger 11 terminates in a piston which cooperates with a horizontal hydraulic cylinder 13. Further, the cylinder 13 is connected to a source of oil under pressure, by way of a pump 14, driven by an electric motor 16. The hydraulic cylinder 13 is controllable to urge the plunger 11 and hence the ram, toward an extended or retracted position.

The end of the vat 10 opposite the ram end, is provided with a vertically slideable gate 17, which affords access to the interior of the vat 10. The gate 17 may be raised or lowered by the hydraulic cylinder arrangement 19, the associated piston of which is connected to the gate 17 by means of a connecting rod 19a. Further, a pair of tracks 20 are symmetrically positioned on each side of the vat 10, is slideably supported in alignment with a pair of tracks 22a positioned on the inner faces of the side walls of the vat 10. The latter pair of tracks 22a engages and supports a plurality of sheet-partitioning and supporting rectangular plates 23c by means of lateral projections 23b extending from the plates 23c. The forward ends of the tracks 20 are each slideably supported on rollers 20a mounted on corresponding upright guides 21a and rectangular openings adjacent the rear ends of the tracks 20 are slideably engaged by bosses 23a.

A track-sliding mechanism is provided, which urges the tracks 20 into and out of the interior of the vat 10, with the raising and lowering of the gate 17. More particularly, the tracks 20 are each provided with a vertically elongated slot 22, which is engaged by a pin 23 laterally projecting from one end of an arm 24. The opposite end of the arm 24 is keyed to a horizontal shaft 25, which is rotatably supported by brackets 26. Further, a pair of oppositely extending arms 27 and 28 are keyed to the shaft 25, and are pin-connected to corresponding turnbuckles 29 and 30. In turn, the opposite ends of the turnbuckles 29 and 30 are each connected to a corresponding bell crank 32 and 33 respectively, which are rotatably supported and which terminate in cam follower rollers 34 and 35. Associated with each of the followers 34 and 35, are the cam members 36 and 37 which project vertically from the gate 17. The cam member 37 is so shaped that upon the raising of the gate 17, the cam member 37, by way of the follower 35 and the connecting linkage and shaft, urges the tracks 20 inwardly into registry with the tracks positioned in the vat 10. Further, the cam member 36 is so shaped that upon the lowering of the gate 17, the cam member 36 urges the tracks outwardly by way of the follower 34 and the connecting linkage and shaft.

In order to securely lock the tracks 20 in their inwardly extended position, there is provided a mechanism actuated by the gate 17 when it is completely opened. This mechanism consists of a rotatable bell crank 40, supporting a locking pin 41 which is slideable in a bore 42 formed in a bracket 43. Moreover, the track 20 is provided with a bore 44 which is in alignment with the bore 42 when the tracks 20 are in registry with the tracks positioned in the vat. The opposite end of the bell crank 40 is connected by way of an adjustable link or rod 46 to the outer end of a lever 47, which is suitably keyed to a shaft 48. The shaft 48 in turn is rotatably supported by a standard 49, and is provided at its other end with an arm 50 extending at an angle to the longitudinal axis of the shaft 48. Further, engaging a vertical tapped bore formed in the free end of the arm 50, is an adjustable screw mem-

ber 51 provided with a lock nut 52, the adjustment of the screw member 51 determining the relative position of the gate, for actuation of the track-locking mechanism.

An angle member 53 whose legs are of different lengths and form an angle of less than 90° with each other, has its shorter leg fastened to the arm 50 by means of a pair of screws 54. Further, secured to the free end of the longer leg of the angle member 53, is the relatively heavy weight 55. The purpose of the weight 55 is to positively urge the track-locking pin 41 to its retracted position upon the lowering of the gate 17. Failure of the pin 41 being removed from the bore 44 before initiation of the track-retracting operation, would result in serious damage to the track-retracting mechanism. It should be noted that the arm 50 and the angle member 53 are so shaped that the weight 55 is clear of the path of the gate 17, and is substantially spaced from the longitudinal axis of the shaft 48.

Considering now the operation of the equipment above described, after the sheets of pulp have been steeped in the caustic solution for the desired period of time, the caustic solution is drained from the vat 10, and the cylinder 13 actuated to advance the ram until the sheets of alkali cellulose have reached the desired press ratio, the expressed liquid being likewise drained from the vat 10. Thereafter, the pressure on the ram 13 is released and the cylinder 19 is actuated to raise the end gate 17. As the gate 17 rises, the cam 37 urges the bell crank 33 to rotate so that through the associated linkage 30 and 28, shaft 25 and arm 24, the tracks 20 are slid into registry with the tracks positioned within the vat 10, and the opening 44 is brought into alignment with the bore 42 and pin 41. Upon approaching its uppermost position, the top of the gate 17 comes into contact with the screw member 51, thereby to rotate the arms 50 and 47 and the shaft 48. The rod 46 is moved downwardly, rotating the bell crank 40 and sliding the pin 41 into the opening 44, to lock the tracks 20 in their inserted position.

The ram is again urged forward by means of the cylinder 13 and the alkali cellulose sheets and the supporting plates are discharged through the open front end of the vat 10. The plates, as they ride along the tracks 20, permit the alkali cellulose sheets to fall from between the plates into any suitable hopper or chute positioned below and between the tracks 20. After the alkali cellulose sheets have been completely discharged, the ram is retracted, carrying the plates which are chain-connected back into the vat 10. The cylinder 19 is then actuated to lower the gate 17 into closed position.

The falling of the gate 17 releases the arm 50, which results in the shaft 48 rotating as a consequence of the torque exerted by the weight 55. The rod 46 is raised by the arm 47, thereby rotating the bell crank 40 in a clockwise direction as viewed in Fig. 2 and withdrawing the pin 41 from the bore 44. Upon further dropping of the gate 17, the cam 36 urges the bell crank 32 to rotate so that through the associated linkage 29 and 27, shaft 25 and arm 24, the tracks 20 are withdrawn from the interior of the vat 10 and the path of the gate 17. The gate 17 is thereafter dropped into its completely closed position and the vat is then ready for another steeping operation.

While there has been described and illustrated a preferred embodiment of the present invention,

it is obvious that numerous omissions and alterations may be made without departing from the spirit thereof.

I claim:

1. A steeping press comprising a vat having a vertically slideable gate positioned at one end thereof, means for raising and lowering said gate, a longitudinally movable track extending in front of said vat, means responsive to the movement of the gate for sliding said track inwardly across the path of said gate, and a mechanism responsive to the movement of said gate for locking said track in its inner position, said mechanism including a weight for normally urging said mechanism to a track-unlocked position.

2. A steeping press comprising a vat having a vertically slideable gate positioned at one end thereof, means for raising and lowering said gate, a longitudinally movable track extending in front of said vat, means responsive to the raising of the gate for sliding said track into said vat, said track having a transverse bore formed therein, and a mechanism including a locking pin and responsive to the raising of said gate for inserting said locking pin into said bore, said mechanism

including a weight for normally withdrawing said pin from said bore.

3. A steeping press comprising a vat having a vertically slideable gate positioned at one end thereof, a longitudinally movable track extending in front of said vat, means for sliding said track into said vat upon the raising of said gate, and out of said vat upon the lowering of said gate, said track having a transverse bore formed therein, a locking pin adapted to engage said bore, a link mechanism operated by said gate for urging said locking pin into engagement with said bore, and a weight so associated with said link mechanism as to normally urge said locking pin out of engagement with said bore.
